UNITED STATES PATENT OFFICE.

CHARLES R. SEDDON, OF BURY, ENGLAND, ASSIGNOR OF ONE-HALF TO
GEORGE BENTLEY AND JOHN BROAD JACKSON, OF SAME PLACE.

MECHANISM FOR IMPARTING MOTION TO SHAKE-FRAMES.

SPECIFICATION forming part of Letters Patent No. 561,529, dated June 2, 1896.

Application filed October 15, 1894. Serial No. 525,982. (No model.)

To all whom it may concern:

Be it known that I, CHARLES ROBERT SEDDON, manager, a subject of the Queen of Great Britain and Ireland, residing at 285 Rochdale 5 Road, Bury, in the county of Lancaster, England, have invented certain Improvements in Mechanisms for Imparting Motion to Shake-Frames, of which the following is a specification.

10 The object of my invention is to provide the operating mechanism for imparting the shaking movement to the shake-frames of paper-making machines or analogous purposes with means whereby the degree of shaking imparted can be regulated and adjusted without stopping the machine or interfering with the connecting-rod and gear or mechanism from which the shaking motion is obtained. This I effect by making the distance 15 between the fulcrum upon which the operating-lever oscillates and the point of attachment thereto or connection therewith of the shake-frame or its equivalent variable or adjustable. This variation or adjustment can 20 be effected by making the said fulcrum movable and fixable in the adjusted position.

I will describe this invention more particularly with reference to the accompanying drawings (illustrating its application to the 25 operation of the shake-frames of paper-making machines) by an example in which the fulcrum on which the lever oscillates is adjustable.

Figure 1 is a side elevation, and Fig. 2 is a 30 plan, of so much of a machine as is necessary to illustrate this invention.

Referring to the drawings, A is part of the shaker-frame of a paper-making machine, and B is the lever, which is connected thereto 40 by the center-pin at D, the said lever B being oscillated by any usual or suitable device through the connecting-rod C. The said lever B is oscillated upon a fulcrum at E, which fulcrum may consist of a pin passing through a 45 slot in the lever B or a sleeve carrying pins through which the lever passes. The said pin or pins is or are carried in bearings in the piece e, which is provided with a nut in which the screw G works, the said screw being capable of being rotated, but not of moving longitudinally in the standard H. Rotation is

imparted to the screw G by means of a hand-wheel M, keyed on a shaft K, mounted in a bearing L and having keyed to it a bevel-wheel J, which gears with another bevel-wheel I, 55 keyed to the screw G. By rotating the hand-wheel M in one or the other direction the screw G is rotated, so that it causes the fulcrum E to move nearer to or farther from the point of attachment or connection of the shaker-frame at D, and thus the length of motion given to the shake-frame can be adjusted as required and with the greatest nicety, in accordance with the kind of paper being manufactured. After the adjustment has been 60 made the fulcrum E is locked in position on the screw G by means of the pinch-nut N.

It will be evident that the invention is not restricted to the precise details shown. For example, the screw G may be operated in any 70 convenient manner, such as by a hand-wheel secured directly to it.

I have described the application to the imparting of the motion to the shake-frames of paper-making machines; but it will be evident that a shaking motion can be imparted in the same way to other devices which require to have a shaking motion imparted to them which it is desirable to make variable or adjustable. 75

I claim as my invention—

The combination of the shake-frame of a paper-making machine with a lever, a fulcrum movable on one end of the lever, means for oscillating the lever at its other end, a pivotal 85 connection between the shake-frame and the lever and located between the said fulcrum and said oscillating means, a screw engaging with and operating the carrier of the said fulcrum, a vertical supporting-standard, H, for 90 the screw, and means for operating the screw to move the fulcrum nearer to or farther from the said pivotal connection without stopping the movement of the shake-frame, substantially as and for the purposes set forth. 95

In testimony whereof I have signed my name to this specification in the presence of two subscribing witnesses.

CHARLES R. SEDDON.
